UNITED STATES PATENT OFFICE.

EDWIN MALCOLM McPHERSON, OF CHICAGO, ILLINOIS.

DESIGN FOR A MEDAL, MEDALLION, OR LUCK-PIECE.

54,433.

Specification for Design.

Patented Feb. 10, 1920.

Application filed June 15, 1918. Serial No. 240,245. Term of patent 3½ years.

To all whom it may concern:

Be it known that I, EDWIN MALCOLM McPHERSON, a citizen of the United States, and resident of Chicago, in the county of Cook, and State of Illinois, have invented a new, original, and ornamental Design for a Medal, Medallion, or Luck-Piece, of which the following is a specification, reference being had to the accompanying drawings, forming part thereof.

The figure is a plan view of a medal, medallion, or luck piece, showing my new design.

I claim:

The ornamental design for a medal, medallion, or luck-piece, as shown.

EDWIN MALCOLM McPHERSON.
